CLAIM

The ornamental design for a go-kart as shown and described.

DESCRIPTION

FIG. 1 is a top-front-left side perspective view of a go-kart embodying our new design;

FIG. 2 is a bottom-front-right side perspective view thereof;

FIG. 3 is a top-rear-right side perspective view thereof;

FIG. 4 is a bottom-rear-right side perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The broken lines in the drawings illustrate portions of the go-kart that form no part of the claimed design.
